C. G. KING.
LATCH FOR BRACELETS AND THE LIKE.
APPLICATION FILED APR. 8, 1919.
1,390,361.

Patented Sept. 13, 1921.

FIG. 1.

FIG. 2.

INVENTOR:
Clifford G. King
By G. K. Woodward
ATTORNEY:

UNITED STATES PATENT OFFICE.

CLIFFORD G. KING, OF PROVIDENCE, RHODE ISLAND, ASSIGNOR TO HIMSELF AND
ARTHUR I. CLARK, OF CRANSTON, RHODE ISLAND.

LATCH FOR BRACELETS AND THE LIKE.

Specification of Letters Patent. Patented Sept. 13, 1921.

1,390,361.

Original application filed June 8, 1918, Serial No. 238,821. Divided and this application filed April 8, 1919. Serial No. 288,461.

To all whom it may concern:

Be it known that I, CLIFFORD G. KING, a citizen of the United States, and a resident of Providence, in the county of Providence and State of Rhode Island, have invented a new and useful Improvement in Latches for Bracelets and the like, of which the following is a specification.

My invention relates to latches for bracelets and the like and more especially to expandible bracelets of the type disclosed in my application Serial No. 238,821 filed June 8, 1918, now Patent No. 1,303,220, dated May 6, 1919, of which this application is a division.

The object of my invention is to provide a latch whereby a bracelet may be opened and closed at a point intermediate the ends thereof, of which, in the case of a wrist watch bracelet, are coupled to the watch. In the drawings which accompany and form a part of this specification—

Figure 1 is an elevation of a bracelet provided with my improved latch, and Fig. 2 is a horizontal section of said latch taken on the line 2—2 of Fig. 1.

In the particular form of my invention selected for illustration outer shells 1 inclose inner tubes 2 and are relatively movable with respect to the same, the spring 3 surrounding the connecting member 4 which is held in position by the key 5, serving to restore the parts to their normal position. Intermediate the ends of the bracelet is a shell 6 provided with two pairs of oppositely arranged apertures 7 near one end thereof and having the hinge member 8 soldered to the other end thereof, said member being connected with the juxtaposed hinge member of the adjacent shell 1 by one of said connecting members 4 in the same way that the tubes and shells of the bracelet are hingedly connected. Located within the shell 6 is a tube 9 one end of which is hingedly connected to the hinge member of the shell adjacent thereto by the connecting member 4.

The tube is provided with two pairs of oppositely arranged apertures 10 which register respectively with the apertures 7 of the shell. The latch consists as shown of two arms each provided with a finger piece 11

arranged to project through one pair of apertures in the tube and shell and each having a lug 12 adapted to project through the other pair of apertures in the tube and to take into the other pair of perforations in the shell, for the purpose of latching the shell and tube together. Preferably resilient means are provided for forcing said arms of the latch outwardly and in the present instance I have shown said arms secured to or formed integral with the spiral spring 13. To separate the two portions of the bracelet the finger pieces are pressed inwardly so that the lugs 10 will clear the shell whereupon the tube may be withdrawn from the shell.

As shown in Fig. 1 the ends of the bracelet are attached to the rings of the watch 14 by means of the snap hooks 15.

It will be obvious that various modifications may be made in the particular embodiment of my invention specifically disclosed herein without departing from my invention as defined by the appended claims.

I claim:

1. An expandible bracelet comprising in combination a series of tubes, a series of shells each embracing a tube, a shell inclosing a latch, said shell being hingedly connected to one of two juxtaposed shells and a tube within said shell, said tube being hingedly connected to the other of said juxtaposed shells.

2. In a bracelet, a tube, a shell embracing said tube, said tube and shell each having two pairs of oppositely arranged apertures near one end thereof, the apertures of the shell registering respectively with those of the tube, and a latch inclosed within said tube, said latch consisting of two arms each provided with a finger piece arranged to project through one pair of apertures in said tube and shell and each provided with a lug arranged to project through the other pair of apertures in said tube and to take into the other pair of apertures in said shell.

3. In a bracelet, a tube, a shell embracing said tube, said tube and shell each having two pairs of oppositely arranged apertures near one end thereof, the apertures of the shell registering with those of the tube, and

a latch inclosed within said tube, said latch consisting of two arms each provided with a finger piece arranged to project through one pair of apertures in said tube and shell and 5 each provided with a lug arranged to project through the other pair of apertures in said tube and to take into the other pair of

apertures in said shell, and resilient means for forcing said arms outwardly.

In testimony whereof, I have hereunto 10 subscribed my name this 5th day of April, 1919.

CLIFFORD G. KING.
